(57) **CLAIM**

The ornamental design for a platform assembly for a roof rack, as shown and described.

DESCRIPTION

FIG. 1 is a perspective view of a platform assembly for a roof rack showing the design of the invention.

FIG. 2 is a front view thereof.

FIG. 3 is a rear view thereof.

FIG. 4 is a side view thereof, the opposite side being a mirror image.

FIG. 5 is another side view, showing ends in detail; and,
FIG. 6 is a top view thereof.

1 Claim, 6 Drawing Sheets

FIG 2

FIG
3

FIG. 6
